J CLARENCE McCARTHY, OF LANCASTER, PENNSYLVANIA, ASSIGNEE TO ARMSTRONG CORK COMPANY, OF LANCASTER, PENNSYLVANIA, A CORPORATION OF PENNSYLVANIA

EMBORESSED FLOOR COVERING

Application filed October 31, 1929. Serial No. 403,820.

This invention relates to embossed floor coverings and is herein particularly described as applied to the manufacture of molded inlaid linoleum.

Linoleum and similar flexible hard surfaced floor coverings have always presented a "hard" appearance to the eye. In fact, one class of patterns which has been singularly successful has been that in which tiling is simulated. Difficulty has also been experienced in getting a soft blending of the pattern elements one into the other. In straight-line linoleum there is a clean, sharp line of demarcation between adjacent pattern elements. In unembossed molded inlaid linoleum the line of junction is wavy in character. This, however, is not a virtue but a defect and does not lead to any blending of the adjacent colors. On the contrary, the line of distinction is marked but such line itself is of an objectionable character.

Because of these defects it has heretofore been impossible to obtain certain desirable decorative effects in linoleum and the like. There is a demand for patterns wherein there is a soft blending of one color into another and wherein there is a surface texture with the pattern un-obtrusively appearing therethrough. Great difficulty is experienced in obtaining such an effect, but I have found that by the provision of tuft-like crests over the surface of the linoleum very desirable effects can be obtained. Preferably these crests are relatively small, averaging, say, $\frac{1}{8}$ of an inch across, and being arranged in a haphazard manner over the entire surface of the goods. Such tuft-like crests may comprise an irregular series of small humps which are serrated so as to soften the effect.

With this type of embossing it is relatively easy to obtain a continuous effect of the character desired. In the molded inlaid process, which is intermittent in its nature, the embossing is obtained by a reciprocable die which works on a limited length only of the material. I have found that contrary to previous experience it is possible with this type of embossing to overlap successive embossed portions without destroying the effect and without the overlap showing. This is of

importance because any break in the character of the texture imparted to the material, as would result if nonoverlapping portions were embossed by such a die, would destroy the effect which it is necessary to obtain.

The invention finds particular value in the molded inlaid process where the irregular line of juncture between adjacent pattern elements cooperates with the small tuft-like crests to produce the blending effect.

In the accompanying drawing, illustrating the present preferred embodiment of the invention as applied to a pattern of the hooked rug type,

Figure 1 is a top plan view of a piece of plain molded inlaid linoleum;

Figure 2 is a plan view of the same piece after it has been embossed according to my invention; and

Figure 3 is a longitudinal section through the embossed goods.

The linoleum shown in the drawing is made by the molded inlaid process, granulated color being supplied through stencils onto a backing 2 so as to form a vari-colored pattern. As shown in Figure 1, the several pattern elements are separated by lines of juncture 3 of the wavy irregular character inherent in the molded inlaid process. It will be noted from Figure 1 that the general effect of the process is to give a pattern with definite monotone color areas which distinguish sharply from one another, but which are separated along wavy lines which are themselves objectionable in appearance. The material itself is smooth and hard surfaced and presents a cold, hard appearance to the eye.

Figure 2 shows the same piece of material after it has been embossed according to my invention. It will be noted that the entire surface of the goods is covered with an irregular series of small crests 4. Each crest is serrated, as indicated at 5. These serrations are quite shallow but are very effective for "softening" the general tone of the material. The serrations extend in different directions in different crests, but lie generally parallel in any given crest.

The several crests formed by the embossing are tuft-like in character and somewhat

reminiscent of carpet, although giving a new and highly ornamental effect. The colors of the pattern are subdued and in general there is a tendency for the colors to blend one into the other. The irregular juncture lines between pattern elements follow an uphill and downdale course over the embossed surface of the linoleum, thus doing away with any sharp lines of separation between adjacent pattern elements.

10 Molded inlaid machines are designed to give a repeat length of 54 inches, and heretofore embossing presses have been provided with dies effective for embossing a 54 inch length at one time. In the present case, however, I have found it highly desirable to emboss a slightly greater length so that when the goods is moved forward and the embossing die is again lowered, it overlaps a portion of the previously embossed material and re-embosses it. I have found that with a surface embossing of the character herein described the overlap does not show and the general effect is of a continuous tufted surface without any change or interruption in the surface character thereof. It is thus possible to produce long lengths of the material without any breaks in the embossing.

15 While it is possible to secure the continuous embossed effect with relatively large and separated embossed interliners, such as are used in tile patterns, I have found that all-over embossed patterns are difficult to produce. If it is attempted to emboss exactly 54 inches and then emboss an adjacent 54 inches, the line of separation shows very distinctly and destroys the effect; while if it is attempted, with other all-over embossed patterns, to overlap the embossing, as herein described, such overlapping shows very clearly, and the net result is that a band of material having a poor decorative effect is produced every 54 inches. However, as above stated, it is possible, where tuft-like crests are provided, to overlap the die without such overlapping being evident in the final product.

20 I have illustrated and described my invention as applied to one type of pattern. It will be understood, however, that it is not thus limited but may be otherwise embodied or practiced within the scope of the following claims.

I claim:

25 1. In the manufacture of flexible hard surfaced floor coverings, the step consisting in forming a series of small serrated humps irregularly arranged over the surface thereof.

2. In the manufacture of flexible hard surfaced floor coverings, the steps consisting in forming a pattern, and forming an irregular series of small serrated humps over the surface thereof, the serrations running in different directions in different humps.

30 3. In the manufacture of flexible hard sur-

faced floor coverings, the steps consisting in forming a pattern, and forming an irregular series of small serrated humps over the surface thereof, the serrations running in different directions in different humps but running generally parallel in any hump.

4. In the manufacture of flexible hard surfaced floor coverings, the step consisting in producing serrated humps over substantially the entire surface thereof.

5. As a new article of manufacture, a flexible hard surfaced floor covering having a plurality of serrated crests embossed over the surface thereof.

6. As a new article of manufacture, a flexible hard surfaced floor covering having a plurality of serrated crests embossed over the surface thereof, the serrations in different crests extending in different directions.

7. As a new article of manufacture, molded inlaid linoleum having adjacent pattern elements connected on lines of juncture possessing irregularities characteristic of molded inlaid linoleum, and having crests embossed over the surface thereof.

8. As a new article of manufacture, a flexible hard surfaced floor covering having small serrated humps over the surface thereof, the serrations running in different directions in different humps.

9. As a new article of manufacture, a flexible hard surfaced floor covering having small serrated humps over the surface thereof, the serrations running in different directions in different humps, but running generally parallel in any hump.

10 10. In the manufacture of flexible hard surfaced floor coverings, the step consisting in forming an irregular series of small serrated humps over the surface thereof, the serrations running in different directions in different humps.

11 11. In the manufacture of flexible hard surfaced floor coverings, the steps consisting in forming a series of crests substantially covering a portion of the surface of the material, then forming a like series of crests over an adjacent portion of the material, and overlapping such portions so that crests originally formed in the first portion are reformed in the second portion.

12 12. As a new article of manufacture, a flexible hard surfaced floor covering having a plurality of crests embossed over the surface thereof, the individual crests being small in crosswise dimension and being arranged in a haphazard manner over substantially the entire surface of the goods.

125 In testimony whereof I have hereunto set my hand.

J CLARENCE McCARTHY.

CERTIFICATE OF CORRECTION.

Patent No. 1,873,001.

August 23, 1932.

J CLARENCE McCARTHY.

It is hereby certified that error appears in the printed specification of the above numbered patent requiring correction as follows: Page 2, line 7, claim 4, strike out the word "substantially", and line 75, strike out the word "entire"; and that the said Letters Patent should be read with these corrections therein that the same may conform to the record of the case in the Patent Office.

Signed and sealed this 22nd day of November, A. D. 1932.
